UNITED STATES PATENT OFFICE.

ALBERT P. SCHMIDT, OF SNYDER, COLORADO.

SPRING ATTACHMENT FOR DRILLING-MACHINES.

1,359,845.

Specification of Letters Patent. Patented Nov. 23, 1920.

Application filed March 7, 1917. Serial No. 153,012.

To all whom it may concern:

Be it known that I, ALBERT P. SCHMIDT, a citizen of the United States, residing at Snyder, in the county of Morgan and State 5 of Colorado, have invented certain new and useful Improvements in Spring Attachments for Drilling-Machines; and I do hereby declare the following to be a full, clear, and exact description of the invention 10 such as will enable others skilled in the art to which it appertains to make and use the same.

The invention relates to a spring attachment for drilling machines.

15 The object of the present invention is to provide a simple, practical and efficient spring attachment for portable drilling machines adapted to enable a steel cable to be employed and to take the jerk out of the 20 drilling machine thereby increasing the durability of the machine and the injury to the frame of the machine to which the latter is subjected when a steel cable is employed without relieving the frame of the 25 jerk of the cable.

With these and other objects in view, the invention consists in the construction and novel combination of parts hereinafter fully described, illustrated in the accompanying 30 drawings and pointed out in the claims hereto appended; it being understood that various changes in the form, proportion, size and minor details of construction, within the scope of the claims, may be resorted 35 to without departing from the spirit or sacrificing any of the advantages of the invention.

In the drawings:

Figure 1 is an end elevation of a portion 40 of a drilling machine provided with a spring attachment constructed in accordance with this invention.

Fig. 2 is a vertical sectional view of the same.

45 Figs. 3 and 4 are detail views illustrating the construction of the slideable and pivotal connection of the foldable derrick member.

Fig. 5 is a horizontal sectional view on the line 5-5 of Fig. 1.

50 Fig. 6 is a detail sectional view on the line 6-6 of Fig. 1.

Fig. 7 is a horizontal sectional view on the line 7-7 of Fig. 1.

Like numerals of reference designate corresponding parts in the several figures of 55 the drawings.

In the accompanying drawings in which is illustrated the preferred embodiment of the invention 1 designates the upright foldable derrick member of a portable well 60 drilling machine having a wheeled frame 2 and provided at opposite sides thereof with inclined braces 3 spaced apart at their upper ends to receive the foldable derrick member 1. The foldable derrick member 1 is connected to the upper ends of the inclined braces by a horizontal pivot 4, which passes through a transversely disposed eye or bearing opening 5 of a bearing plate 6. The bearing plate 6, which is pro- 70 vided with upper and lower slots 7, is connected to derrick member 1 by bolts 8 extending through the slot 7 and adapted to permit a sliding movement of the derrick member 1 with relation to the transverse pivot 4, 75 which is in the form of a bolt. The derrick member 1 is adapted to fold to a horizontal position upon the machine in the usual manner and when arranged in an upright position its lower portion is received within 80 a horizontally disposed guide 9 provided with inwardly projecting spaced lugs 10 located at the side edges of the derrick member 1 and adapted to receive and guide the said member between them. The horizontal 85 guide 9 is detachably bolted to the inclined braces 3 at 11 and the said guide 9 is removed when it is desired to fold the derrick member 1.

The lower end of the derrick member is 90 arranged upon a coiled cushioning spring 12 when the said derrick member is in an upright operative position. The spring 12 is adapted to relieve the frame of the machine of the jerk of the cable 13 and it enables a 95 wire cable to be employed instead of the ordinary rope, thereby increasing the durability of the machine and preventing the jar, strain and injurious effect on the frame which necessarily results when a wire cable is employed 100 without cushioning means. The coiled spring is supported upon a plate 14 arranged at the end of the frame of the machine at the outer face of the transverse end beam or member 15 and secured to the same by approximately 105 L-shaped hanger bolts 16 having horizontal upper arms and lower depending vertical arms. The upper arms 17 extend through the transverse beam or member 15 and the downwardly extending vertical arms pass 110 through the plate 14. The ends of the hanger bolts are threaded for the reception of nuts

18 and 19. The plate is also designed to be supported by a jack 20 of any ordinary construction, which is placed centrally beneath the plate and the lower end of the spring, 5 which is preferably seated in a recess 21 of the supporting plate 14. Any suitable means may be employed for fastening the spring directly to the lower end of the beam, if desired, but the mounting of the spring permanently upon the supporting plate in this 10 manner will be sufficient and the spring, in practice, remains upon the supporting plate while the lower end of the derrick member is swung upwardly from the spring when the derrick member is folded upon the frame of the machine.

The derrick member is designed to contain the usual over-head pulley 22 for the reception of the cable 23, which carries the 20 drilling tools 24 adapted to operate in a well casing 25 and to enable the same to be sunk in the ground in the usual manner. In the operation of the drilling machine, the drilling tools are raised and dropped in the 25 usual manner. The sliding connection between the derrick member 1 and the frame of the machine, together with the cushioning device, will relieve the frame of the machine of the jerk of the cable.

30 What is claimed is:

1. An apparatus of the character described comprising a frame, a pair of upwardly extending bracing members arranged on the frame, a derrick member pivotally and reciprocally mounted between said bracing members, a bearing plate arranged on said derrick member intermediate its ends thereof and having a transverse bearing opening therein, a pivot element extending through 35 said bearing opening and the upper ends of

said bracing members, said bearing plate having elongated slots extending longitudinally thereof on opposite sides of the bearing opening therein, retaining elements extending through said derrick member and adapted to partake of a reciprocatory movement in the elongated slot of said bearing member; and a coil spring mounted on said frame and supporting said derrick member. 45

2. The combination with a support, a pair 50 of vertically disposed beams mounted thereon, of a standard pivoted intermediate its ends between the beams and capable of being disposed either in a horizontal or vertical position, said standard having sliding connection with the beam at the point of pivotal connection, means carried by the standard for guiding an element of a well drilling apparatus, and cushioning means engaging the standard when the latter is in a vertical 55 position.

3. The combination with a support and a pair of vertically disposed beams mounted thereon, of a plate provided with longitudinal slots, a drill beam, a bearing carried by 60 the plate, a pivot extending through the bearing and journaled in the beam, fastenings extending through the beam and slots in the plate to permit the beam to move longitudinally, and shock absorbing means engaging one end of the drill beam during such 65 longitudinal movement, the drill beam being capable of being disposed in a horizontal position when not in use.

In testimony whereof I affix my signature in presence of two witnesses.

ALBERT P. SCHMIDT.
